ATTORNEY.S,

UNITED STATES PATENT OFFICE

MORITZ L. MUELLER, OF SEATTLE, WASHINGTON, ASSIGNOR TO GENERAL DRY KILN COMPANY, OF PORTLAND, OREGON, A CORPORATION

LUMBER-DRYING KILN

Application filed July 3, 1929. Serial No. 375,800.

This invention relates to lumber drying kilns of the character of that shown in my co-pending application, Serial Number 346,667, filed March 12th, 1929, and it has for its object to provide a kiln presenting marked features of advantage and improvement over the devices of the prior art, as will be more particularly pointed out in the detailed description which follows.

10 In the accompanying drawings:

Fig. 1 is a view partly in plan and partly in horizontal section of a kiln constructed in accordance with the invention,

15 Fig. 2 is a vertical sectional view thereof,

Fig. 3 is a transverse vertical sectional view,

Fig. 4 is a fragmentary longitudinal and sectional view upon an enlarged scale,

20 Fig. 5 is a view partly in horizontal section and partly in plan of a modified form of kiln,

Fig. 6 is a longitudinal sectional view of the kiln illustrated in Fig. 5, with certain of the parts omitted,

25 Fig. 7 is a fragmentary longitudinal sectional view through a part of the kiln, upon an enlarged scale, and

Fig. 8 is a transverse vertical sectional view 30 of the modified form of kiln.

In the form of the invention illustrated in Figs. 1 to 4, each kiln chamber comprises the side walls 5, which rest upon the concrete foundation 6, and an arched roof 7, which is 35 formed upon the arc of a circle. The air circulating means consists of a battery of fans 8, that are mounted upon a line shaft 9, the latter being suspended by hangers 10 from the central portion of the dome-like roof.

40 The opposite sides of the interior of the roof are divided into separate chambers 11 and 12, by a longitudinally extending zig-zag partition 13. This partition comprises the longitudinally extending runs 14 and the trans-

45 verse runs 15 and 16, and it is in these latter runs that the fans 8 are disposed. The fans may have their blades set to discharge in opposition to each other. That is, the fans 8^a—8^b, in Fig. 1, may discharge toward each 50 other when the line shaft is rotated in one

direction and discharge away from each other when the line shaft is rotated in the other direction. Thus, it will be clear that the chamber 11 may be either the discharge or the intake chamber for the fans, according to 55 their direction of rotation, and that the same is true with respect to the chamber 12. However, the fans may all discharge in the same direction, if desired.

Batteries of steam pipes or like air heating 60 means are disposed, as indicated at 16, and it will be understood that any other suitable air conditioning elements, commonly employed in lumber drying kilns, may be disposed in the path of the moving air.

55 By referring to Fig. 1, it will be seen that the dispositioning of the longitudinal runs 14, of the partition, creates a series of bays A, along the length of the line shaft, and immediately below the ceiling or roof. A separate 70 fresh air intake pipe 18 is disposed in the roof above each of these bays, said pipes being provided with hinged caps 19, that are adjusted upon their hinge mountings 20, by means of the operating rods 21 and 22. The 75 operating rod 21 is connected to the crank arm 23 of each alternate ventilator pipe cap 19, while the rod 22 is connected to the intermediate crank arms 24 of the intermediate ventilator pipe caps 19. Thus, it is clear that 80

fresh air in any desired amount may be admitted to the bays A upon either side of the fans. The vents provided by these fresh air pipes permit fresh air to enter each fan in equal volume, or permits stale air to escape 85 in equal quantity uniformly throughout the length of the kiln. This assures even humidity reduction with respect to every load of lumber spaced longitudinally along the kiln.

These vents also act as inspection and hand 90 holes for the bearings of the fan on the line shaft, so that these bearings may be kept properly tightened and lubricated, and may be frequently inspected without the necessity of the operator entering the interior of the 95 kiln. In some types of kilns heretofore proposed, the intake of fresh air to the fresh air ducts has been from a point adjacent the end of the kiln, and through fresh air conduits 100 disposed in a sort of basement beneath the

5 kiln. Not only are such basements expensive to construct, but it is extremely difficult to secure an even flow of air throughout the length of the kiln where the air has to be taken in from an end of the duct, because the drag or friction on the air, slows its flow to such an extent that those ports remote from the entrance end of the duct do not receive the same free supply of air as those ports adjacent the entrance end of the duct.

10 The most desirable achievement in dry kiln construction is to secure such a combination and correlation of the parts as will insure absolute uniformity of drying conditions throughout the length and height and width of the kilns. If uniformity of drying conditions is not attained, then degrading of the lumber results, because if any one portion of the lumber dries faster than another portion, warping, checking or cracking is almost certain to occur. By providing a plurality of air intake pipes, freely open to the atmosphere, and disposed at such frequent intervals throughout the length of the kiln that each bay A receives an independent supply of fresh air directly from the atmosphere, and by providing the alternate closures 19 with common operating members to insure that each closure will be opened to the same degree, I am able to secure absolute uniformity of air flow throughout the entire length of the kiln, and I do this in conjunction with air circulating apparatus disposed immediately below a roof of stream line construction, which aids in maintaining a steady and even flow of air laterally of the kiln, past the heating unit 16, and transversely through the piles of lumber 25, that are piled in spaced courses upon trucks 26, mounted to travel on trackrails 27. Rotation is imparted to the line shaft by any suitable driving means, such as the motor 28, and drive chain connections 29.

15 To close the space above the piles of lumber against cross flow of air, which might interfere with the forced circulation through the piles of lumber, I dispose panels 30 longitudinally of the kiln and at such angles that they coact with the chambers 11 and 12, in forming large throats at the entrances to the spaces 31 and 32 between the sides of the piles of the lumber and the kiln walls.

20 The device of the present application is like that of my copending application, above referred to, in that the forcing of hot air downwardly into the chamber 32 (see Fig. 3) causes a lateral diffusion of the air into the lumber, due to the opposing forces set up by the downwardly moving body of air encountering the air which tends to start to rise again after it has lost the downward momentum imparted to it by the fans. The moving of a very large volume of air is greatly facilitated by the construction described, because

25 of the stream line effect of the roof and the

large throats constituting the entrance to the spaces 31—32, it being understood that the direction of air flow may be reversed by reversing the direction of the rotation of the fans, and that either of the chambers 31—32 may constitute the pressure side of the load, according to the direction of such rotation.

30 It is a well known fact that any resistance offered to the passage of the air cuts down the efficiency of ordinary propeller-type fans, to a very marked extent. For fans of this character, it is essential that the air passages be free and unobstructed. By attaining this object in the construction of the kiln, I am able to use these very simple and cheap fans to move large volumes of air over the surfaces to be dried, in a short time.

35 A further advantage of the arrangement described, is that the locating of the radiation in the roof and adjacent the fans, aids in increasing the air flow by creating a suction or rising tendency of the air toward the intake sides of the fans. Another difficulty experienced in lumber drying kilns is obviated by a feature of the present construction in that the panels 30 are terminated short of the end wall of the kiln, as indicated at 33 (see Fig. 2).

40 By virtue of this construction, any air leakage about the doors 34, through which the trucks are introduced into the kilns, is neutralized. It has been the experience that air leakage about the doors at the ends of the kilns has interfered with the maintenance of uniform drying conditions with respect to those loads of lumber adjacent said doors. By disposing the air circulating means overhead and by providing the special entrances 33 to the air circulating means at a point between the doors and the end truck 45 loads of lumbers, air leakage about the doors is neutralized and its deleterious effects prevented. That is to say, if the fans are rotating in one direction, air leakage around one door is drawn directly into the circulatory system instead of having to pass through a load of lumber on its way to the circulatory system, while a blast of hot air is discharged downwardly over the other door, and vice versa. The construction described acts to

50 prevent air, which leaks past the door and around the door from passing through the ends of the loads of lumber which adjoin the door, in its travel to a suction chamber, which is normally located farther away from the door than the entrances 33. Since automatically operated dampers of various kinds are in common use in conjunction with the operation of lumber drying kilns, it will be readily understood that the automatic operation of the dampers constituted by the caps 19, of the fresh air pipes, is within the purview of my invention.

55 The form of the invention illustrated in Figs. 5, 6, 7, and 8, is very similar to that

illustrated in Figs. 1 to 4, and in so far as they have features in common, the same reference characters have been applied. The construction of this modified form differs from the form illustrated in Figs. 1 to 4, in that the underface of the roof 40, of the kiln, is on the arc of a parabola, instead of being upon the arc of a circle, and that the bearings 10^a of the line shaft of the fan are supported upon the transversely extending concrete beams 41, by which the side walls 5 of the kiln are tied together. Steam pipes, or other suitable heating means are disposed, as indicated at 43. A cut-off baffle plate 44 carries a canvas baffle tip 45 at its lower edge, which rests upon the upper surfaces of the piles of lumber, and prevents the cross passage of the air currents. The formation of the roof upon the arc of a parabola results in discharging the air currents against the side walls of the kiln in such manner that the side walls themselves constitute baffles which impart such a lateral kick back to the air currents as to direct them obliquely against the exposed edges of the boards that are piled in spaced courses upon the lumber trucks, these boards, in turn, deflecting these obliquely discharged air currents laterally through the upper courses of the piles of lumber, while such air as cannot find its way through these courses fast enough, continues down the side walls of the kiln and meeting the previously discharging upwardly rising currents of air, is diffused laterally through the lower courses of the piles of lumber, so that all portions of the load receive an ample volume of heated air. The bay A' formed between the transversely extending runs of the partition have their bottoms closed, (see Fig. 8) by sheets 46. These sheets, as well as the transit panels 30, are removable to give access to the fan chambers. In both forms of the invention, the continued movement of warm air currents over the underside of the ceiling, prevents the condensate and resulting drip, so common in those types of kilns, in which the air circulating means is disposed at the bottom of the kiln. By disposing the line shaft in the top of the kiln, the permanent alignment of the same is secured.

Another advantage of disposing the circulating means overhead is that the fans, their bearings and the associated air ducts are in a position where water, acids, sawdust, chips or broken stock cannot come in contact with them.

In the employment of kilns having the air ducts at the bottom of the kilns, it is common practice for the workmen to walk along these ducts, with the resultant liability of breakage or damage to the same. The permanent shaft alignment referred to is insured by the bays being anchored to an arch roof which cannot sag longitudinally or settle

locally, as is the case with flat ground foundations.

The parabolic form of roof herein shown and described possesses great strength and is very economical to construct, while, at the same time, having the inherent advantage above referred to, with respect to the direction of air flow. A ceiling of arched formation reduces eddy currents and increases the output of the fans, as compared to the rectangular basement or flat roof types of kilns so commonly employed. While it is possible to provide rounded corners with a flat roof construction, to reduce eddy currents, the arched roof gives this effect at least expense, and with increased strength. By locating the fans with their bearing stands on concrete beams, supported by walls which act as trusses in transmitting the load to the ground, the alignment of the fan drive shaft is rendered much more permanent than where the fan system is located in a basement, and comprises bearings supported directly on the ground and, therefore, subject to local settlement.

Further, when the fans are located in a basement, it is impossible to inspect, repair or lubricate the same while the kiln is running, because of the location of piles of lumber over the bearings, and because of the heat of the kiln and the congested relation with moving parts. By locating the fan equipment above the lumber, and under the ceiling and providing means for access to the bearings of the fan from the exterior of the kiln, a workman may see, or reach the bearings without entering the kiln, and this is an important advantage.

Dropping of water, or condensate, sawdust, pitch, broken pieces of lumber and the like into the fans of the basement types of kilns causes the fan equipment to rust, and become laden with pitch, and sometimes to be wrecked. The overhead fans are free of these objections.

It is to be understood that the invention is not limited to the precise construction set forth, but that it includes within its purview whatever changes fairly come within either the spirit or the terms of the appended claims.

Having described my invention, what I claim is:

1. A kiln of the character described, having an arched roof, a partition disposed beneath said arched roof and dividing the space therebeneath into two chambers, a plurality of air circulating elements disposed in said partition, a plurality of air intakes disposed longitudinally along the top of the kiln, and means for operating all of said intakes uniformly to the same degree and in unison.

2. A kiln of the character described, having an arched roof, a partition disposed beneath said arched roof and dividing the space therebeneath into two chambers, a plurality

of air circulating elements disposed in said partition, a plurality of air intakes disposed longitudinally along the top of the kiln, means for operating all of said intakes uniformly to the same degree and in unison, there being one of said air intakes for each air circulating means.

3. A kiln of the character described, having an arched roof, a partition beneath said roof dividing the space therebeneath into two chambers, a plurality of circulating fans in said partition, a plurality of air intakes disposed longitudinally along said roof, a common operating member for each alternate air intake, and another common operating member for the intermediate air intakes.

4. A kiln of the character described, having an arched roof, a partition beneath said roof, dividing the space therebeneath into two chambers, a plurality of circulating fans in said partition, a plurality of air intakes disposed longitudinally along said roof, a common operating member for each alternate air intake, and another common operating member for the intermediate air intakes, there being one of said air intakes for each of said fans.

5. A structure of the character described, comprising an arched roof, the underface of which presents a curvature on the arc of a parabola, transversely of the kiln, air circulating means disposed beneath said roof and arranged to set up an air circulation laterally across the kiln, a longitudinally extending partition in which the air circulating means is disposed, which divides the kiln longitudinally into two chambers, and a plurality of fresh air intakes disposed longitudinally along the top of the kiln, each alternate air intake being common to one of said chambers, and the intermediate air intakes being common to the other of said chambers.

6. A structure of the character described, comprising an arched roof, the underface of which presents a curvature on the arc of a parabola, transversely of the kiln, air circulating means disposed beneath said roof and arranged to set up an air circulation laterally across the kiln, a longitudinally extending partition in which the air circulating means is disposed, which divides the kiln longitudinally into two chambers, a plurality of fresh air intakes disposed longitudinally along the top of the kiln, each alternate air intake being common to one of said chambers, and the intermediate air intakes being common to the other of said chambers, and a common operating means for all of the air intakes of one group, and a second common operating means for all of the air intakes of the other group.

7. A structure of the character described, comprising an arched roof, the underface of which presents a curvature on the arc of a parabola, transversely of the kiln, air circulating means disposed beneath said roof and

arranged to set up an air circulation laterally across the kiln, a longitudinally extending partition in which the air circulating means is disposed, which divides the kiln longitudinally into two chambers, a plurality of fresh air intakes disposed longitudinally along the top of the kiln, each alternate air intake being common to one of said chambers, and intermediate air intakes being common to the other of said chambers, hinged covers for all of said air intakes, upstanding crank arms carried by said hinged covers, a common operating member engaging all of the crank arms of one of the groups of the air intake covers, and a common operating rod engaging all of the crank arms of the other group of air intake covers.

8. The combination with a kiln, of an air circulating means disposed between the roof of the kiln, and the lumber therein, and arranged to discharge air transversely of the kiln, there being an air passage between that portion of the lumber space of the kiln adjacent the entrance doors thereof, and the air circulating means to permit the direct drawing into the air circulation of the kiln of such air as may leak past said doors.

9. The combination with a kiln, of a longitudinally disposed series of fans beneath the roof of the kiln, and doors for said kiln, and a partition separating said fans from the lumber receiving space of the kiln, which partition terminates short of the end walls of the kiln to permit the direct entry into the circulatory system of the kiln of such air as may leak past said end doors of the kiln.

10. The combination with a kiln having an arched roof, of a partition dividing the space within said group longitudinally into two compartments, a plurality of fans in said partition for setting up a circulation of air transversely of the kiln, an element extending longitudinally of the kiln which prevents transverse flow of the air across the tops of the piles of lumber in the kiln, and end doors for said kiln, said members terminating short of the end walls of the kiln to leave passages through which air which leaks past the end walls of the kiln may find its way directly to the circulatory system of the kiln without passing through the ends of the piles of lumber.

11. A kiln of the character described, having an arched roof, a partition beneath said roof dividing the space therebeneath into two chambers having a series of oppositely facing bays, a plurality of circulating fans in said partition discharging into said bays, and an individual air intake for each of said bays.

12. A kiln of the character described, having an arched roof, a partition beneath said roof dividing the space therebeneath into two chambers having a series of oppositely facing bays, a plurality of circulating fans in said partition, discharging into said bays, and an

individual air intake for each of said bays and means for operating the air intakes.

13. A kiln of the character described, having a roof adapted to direct air circulation within the kiln, a partition disposed beneath said roof and dividing the space therebeneath into two chambers, a plurality of air circulating elements disposed into said partition, a plurality of air intakes disposed longitudinally along the top of the kiln, and means for operating all of said intakes uniformly to the same degree and in unison.

14. A kiln of the character described, having a roof adapted to direct air circulation within the kiln, a partition beneath said roof dividing the space therebeneath into two chambers, a plurality of circulating fans in said partition, a plurality of air intakes disposed longitudinally along said roof, a common operating member for each alternate air intake, and another common operating member for the intermediate air intakes.

In testimony whereof I affix my signature.
MORITZ L. MUELLER.
